HOLDER FOR ELECTRIC FLATIRONS

Lee E. Traxler, Niles, Mich.

Application August 17, 1948, Serial No. 44,786

3 Claims. (Cl. 248—117.5)

1

This invention relates to holders for electric flatirons, and has for its principal object to provide a simple device to receive a hot iron and to hold it well spaced from the wall or other support, and provide a convenient and safe storage reel for the electric cord.

In the accompanying drawings:

Fig. 1 is an elevation showing the holder with an iron and cord stored;

Fig. 2 is a similar elevation of the holder alone;

Fig. 3 is a vertical section on the line 3—3 of Fig. 2 with the cord indicated on the reel;

Fig. 4 is a transverse section on the line 4—4 of Fig. 2; and

Figs. 5 and 6 are perspective views of two parts used to make up the holder.

The holder includes a generally flat base portion 10 adapted to be made fast on a wall or other support 11 by screws or the like 12. By giving the base material bends or angles 13, 14, 15, 16, it is provided with top and bottom flanges 17 and 18 offset outwardly to space the iron 19 from the wall or support and form a storage reel for the cord 20.

The iron 19 is yieldingly supported by side flanges 21 and 22 curved inwardly after the fashion shown in the drawings to form a downwardly tapering pocket or socket generally conforming to the shape of the iron 19.

As here shown, the flanges 21 and 22 are integral with a base piece 23, separate from the base 10 and secured to it by screws 12, which make the holder fast to the wall 11. The base piece 23 is also provided with a curved arm or finger 24, which guides the point 25 of the iron as it is inserted in the storage position and prevents it striking against the right angular portion 26 connecting the base with the bottom flange 18.

One embodiment of the invention that has been found satisfactory in use is made from 20-gauge sheet aluminum. That material has sufficient resiliency and strength to hold the iron after the fashion shown in Fig. 1, and it is ductile enough to permit the side flanges 21 and 22 to be bent easily to conform to the shape of the iron being stored.

In this embodiment, the top and bottom flanges are approximately $\frac{5}{8}$ " from the wall or support

2

11, and under actual test an iron with the current on full has been stored for four hours without injury to the wall.

The lower end of the bottom flange 18 is turned outwardly at 27 to form a stop 28 to insure that the iron will not at any time pass through the socket formed by the side flanges 21 and 22 and fall. Preferably, as shown, the stop 28 is slotted at 29 to receive the point 25 of the iron and engage its sides, as indicated at 30.

In many if not most instances, the side flanges 21 and 22 will support the iron slightly above the position shown in Fig. 1 and maintain its weight solely by their resilient strength. The result is a mild but firm grasp on the iron that holds it securely in place against the top and bottom flanges 17 and 18.

It is contemplated that the side flanges 21 and 22 may be in one piece with the base 10. The two-piece structure here shown has some advantage of economy of manufacture due to the simpler operations and the elimination of waste material.

I claim:

1. In an iron holder, a base adapted to be mounted on a support, top and bottom flanges offset from the base and projecting in opposite directions to space the iron from the support and form a reel for the cord, and spaced side flanges on the base to grasp the iron and hold it against said top and bottom flanges.
2. In an iron holder, a base adapted to be mounted on a support, top and bottom flanges offset from the base and projecting in opposite directions, and spaced side flanges on the base to grasp the iron and hold it against said top and bottom flanges.
3. In an iron holder, a base adapted to be mounted on a support, top and bottom flanges offset from the base and projecting in opposite directions to space the iron from the support and form a reel for the cord, spaced side flanges on the base to grasp the iron and hold it against said top and bottom flanges, and a stop on the bottom flange to limit the downward movement of the iron.

LEE E. TRAXLER.
